UNITED STATES PATENT OFFICE.

JOHN E. SEMPLE, OF SEWICKLEY, PENNSYLVANIA.

PROJECTILE

1,131,164.

Specification of Letters Patent.

Patented Mar. 9, 1915.

Application filed April 29, 1914. Serial No. 835,131.

To all whom it may concern:

Be it known that I, JOHN B. SEMPLE, residing at Sewickley, in the county of Allegheny and State of Pennsylvania, a citizen of the United States, have invented or discovered certain new and useful Improvements in Projectiles, of which improvements the following is a specification.

This invention relates to the means employed for effecting detonation of the burster-charges of projectiles; and is particularly concerned in guarding the main body of the burster-charge from explosion, in case of premature explosion of the sensitive element in the detonator.

The high-power explosives now ordinarily employed for the burster-charges of projectiles are inert to ordinary shocks and require for their efficient detonation the detonation of other bodies of explosive arranged in proximity to them. Accordingly, in the train of operation from the percussion-cap (or other instrumentality with which explosion begins) and the burster-charge, there is required a relatively sensitive detonator.

Present-day conditions require that the material of which this detonator is composed shall be one which will detonate on ignition. The available materials which will meet this requirement are few; fulminate of mercury is one of them; but all of them are very unstable compounds, and sensitive to shock and compression. The danger incident to their use is lest they be exploded prematurely, in careless handling of the projectiles or otherwise, and in premature explosion explode the main burster-charge prematurely.

It has heretofore been proposed to so arrange the detonator that it shall have a motion of translation when assembled in the projectile structure—a motion of translation with relation to the main burster-charge; that in its proximate position with respect to the burster-charge it shall on explosion impart explosion to that charge, but in its remote position it shall be incapable of doing so: that is to say, if it be exploded when in its remote position, it will have no effect to explode the main charge. And this proposal involves also the provision that normally the detonator shall be in its remote position and shall come to its proximate position only by the transpiring of conditions incident to the firing, flight, or striking of the projectile.

My present invention is concerned with a projectile which includes a burster-charge and a detonator-charge, and in which the two said charges are movable, one relatively to the other, to the end that they may be brought from relative positions in which the detonator-charge is in case of explosion incapable of imparting explosion to the burster-charge to relative positions in which the contrary is true.

More specifically, my invention consists in the structure and arrangement of parts which condition and control such relative positions and such relative movability.

The accompanying drawings illustrate my invention.

Figure 1 is a view in longitudinal section through the base-plug and adjacent parts of a projectile in which my invention is incorporated; Fig. 2 is a view in transverse section, the plane of section being indicated at II—II, Fig. 1; Fig. 3 is a view otherwise identical with Fig. 2, but showing the movable parts in their alternate positions; and Fig. 4 is a fragmentary view in longitudinal section, on the line IV—IV, Fig. 2.

The cavity of the projectile, within which the burster-charge is contained, is indicated at 1; 2 is the base-plug. Adjacent the burster-charge (and, in this case, within a separate chamber segregated by a thin partition wall) is a "booster" charge B: that is a reinforcing charge, transmitting detonation from the detonator to the main charge. This "booster" charge forms no part of my present invention; it will be understood that, in consequence of its detonation, the main charge is detonated; and for present purposes it may be regarded as merely a part of the burster-charge.

D is the detonator charge—the charge which detonates in sequence upon the firing of the fuse or other instrumentality with which explosion begins and which by detonation imparts (when the parts are in proper relative positions) explosion to the burster-charge. In earlier constructions the detonator-charge has been caused to move from its remote position to its position of operative proximity to the burster-charge in consequence of the arrested motion of the projectile in flight or on impact; according to my present invention relative movement of the two parts is effected by the centrifugal force imparted by the projectile in its flight.

While either member of the pair of co-operating parts named (detonator and burster-charge) may be the movable one, the detonator is conveniently made movable. Accordingly, the detonator D, conveniently borne in a suitable carrier 6, is arranged in a runway 3. The runway, instead of extending longitudinally of the projectile (the arrangement heretofore employed) extends in such direction with relation to the axis of rotation that as the projectile flies the detonator will be impelled by centrifugal force along its runway. Furthermore, the disposition of the burster-charge (or, in this case, of the booster, which as I have said is for present purposes to be considered together with and as part of the burster-charge) is such that the detonator when at one end of its range of traverse in its runway is remote from and is at the other end in operative proximity to the burster-charge.

Manifestly any disposition of the detonator runway, such as to bring it at one part farther from the axis of rotation than at another part is a disposition such as tends to afford the desired result; and manifestly considerable latitude is permissible in refinements of structure in this regard; but, having now pointed out the essentials of structure (and in the claims I shall define the arrangement of the runway broadly as "transverse"), I shall by way of example define my preferred arrangement. As shown in the drawings, the runway 3 for the detonator passes through the axis of rotation of the projectile, from side to side, and in a line at right angles to that axis.

The detonator D is conveniently borne in a weighted carrier 6. Suitable means are employed for holding this detonator element in its runway in a position remote from the burster-charge. I do not limit my invention to any specific means, nor to means rendered inactive in any particular manner, nor under any particular circumstances; but I preferably employ means which are rendered ineffective automatically on the firing of the projectile from a gun, and (more specifically) means rendered ineffective by the centrifugal force imparted by the flying projectile. My preferred construction, which is shown and described by way of example, consists of a pair of bolts 4, movable in radial passageways, held centripetally in engagement with the detonator by springs or other suitable instrumentalities, but moving centrifugally as the projectile flies, overcoming the tension of the springs or the effect of other instrumentalities, and when so moving leaving the detonator free in its passageway, to respond to centrifugal impulse. The passageways for the bolts 4 admit of considerable latitude in arrangement, but preferably they are

aligned and form in fact a single passageway 5. Like runway 3, this single passageway preferably extends through the axis of rotation, of the projectile, at right angles to that axis, and at right angles to runway 3 also; and the passageway for the bolts and the runway for the detonator are preferably, though not necessarily, arranged with their individual axes in a common plane. It is sufficient that the passageway intersect the detonator runway and that in consequence the bolts 4 obstruct in the desired manner the movement of the detonator. The detonator carrier 6 is preferably perforate and the perforation through it, when it is properly placed, renders the bolt passageway continuous; and when the carrier is in this position, the detonator is remote from the burster charge. In this position the detonator element may be engaged and held by bolts 4, as shown in Fig. 2. The weight of the detonator element is such and so disposed that when in the position shown in Fig. 2 it will, if released by bolts 4, move under the centrifugal force of the flying projectile, and bring the detonator to operative proximity to the burster charge.

The strength and proportion of parts and the spaces to rearward of the detonator are such that when in its remote position (Fig. 2), if it be accidentally exploded, the effects of explosion are isolated and ineffective to explode the burster charge.

I preferably add to the parts as thus far described, mechanical provision against retrograde movement of the detonator in its runway, when once it has advanced. The structure manifestly admits of the employment of various expedients to that end; and, while my invention broadly covers all such expedients, convenient and adequate means to the end stated are shown in the drawings. A block 7 lies normally inactive, in the position shown in Fig. 1; but when the detonator advances to operative position, this block 7, under the stress of centrifugal force as the projectile flies, swings into runway 3, to rearward of the detonator element, to oppose its retrogression.

The arrangement of the percussion cap, or other initial firing instrumentality, and of the operative connection from it to the detonator, when the latter is in advanced position, form no part of my invention in broadest terms. I show, by way of illustration, the fuse structure 8, and an open passage for the flash of firing from such fuse to the runway 3, at a point rearward of the detonator when advanced.

For structural purposes, the bore through the base-plug to provide a runway for the detonator, may be enlarged by a counterbore 9 at the rear end (rear with respect to the direction of advance of the detonator) and

in this counterbore may be introduced the block 10, closing the counterbore externally (or rearwardly); this block 10 being provided with a sleeve to afford a continuous runway of uniform diameter for the detonator. The sleeve may be saw-cut, as at 11, to allow the passage of the ignition flame. The lock member 7 may be arranged in the space between the sleeve and the counterbore 10 in which the sleeve extends. The passage-way for the bolts 4 will also be bored from the outside of the base plug, and suitably closed when the structure is assembled.

Figs. 1 and 2 show the structure in normal, inoperative position. When the parts are in the positions there shown, the detonator charge D, though it should accidentally be exploded, will be ineffective to explode the body B, which is part of the burster-charge. When the projectile bearing these parts is fired from a gun, and is in flight, the gates 4 will open, the detonator element 6 will advance, and these parts will occupy the relative positions shown in Fig. 3. Consequent upon the advance of the detonator element, the latch block 7 will swing to its runway obstructing position, serving to prevent retrogression of the detonator, whatever shocks the flying projectile may encounter. When the projectile hits, the percussion-cap or other initial instrumentality will be operated, and explosion of the shell will follow in the sequence of operations already sufficiently indicated.

I claim as my invention:

1. In an explosive projectile, the combination of a burster charge and a detonator charge movable the one with respect to the other, under centrifugal force on the rotation of the projectile, from positions of relative remoteness, to detonation-imparting positions.

2. In an explosive projectile, the combination of a burster charge, a fuse, and a detonator charge, the said detonator charge being movable with respect to the fuse on the one hand and the burster charge on the other by the rotation of the projectile, from a position remote from the burster charge to a position of operative relationship to the fuse on the one hand and to the burster charge on the other.

3. In an explosive projectile the combination of a burster-charge chamber, a detonator runway extending transversely with respect to the axis of rotation of the projectile and from a remote point to a point of operative proximity to said burster-charge chamber, a detonator movable in said runway by rotation of the projectile from the said remote to the said proximate

point, and means for firing the said detonator when in advanced position.

4. In an explosive projectile the combination of a detonator runway extending transversely to the axis of rotation of the projectile, a detonator movable therein by the rotation of the projectile, and means operated by the rotation of the projectile for preventing retrograde movement of said detonator in its runway.

5. In an explosive projectile the combination of a transverse runway, a detonator charge movable in said runway by rotation of the projectile and means for holding said detonator charge against such movement.

6. In an explosive projectile the combination of a runway, a detonator charge movable in said runway by rotation of the projectile, and means rendered ineffective by the rotation of the projectile holding said detonator charge against such movement.

7. In an explosive projectile the combination of a runway, a detonator charge movable in said runway by rotation of the projectile, means for holding said detonator charge against forward movement, and means rendered effective by the rotation of the projectile holding said detonator charge against retrograde movement.

8. In an explosive projectile, a runway extending transversely of said projectile, a second runway extending transversely to and intersecting the runway first named, a detonator carrier movable within the runway first named and provided with a recess which normally registers with the second named runway, and means for preventing retrograde movement of the said carrier in its runway.

9. In an explosive projectile a runway extending transversely of said projectile, a second runway extending transversely to and intersecting the runway first named, a detonator carrier movable within the runway first named and provided with a recess which normally registers with the second named runway, and a locking bolt movable within the second named runway.

10. In an explosive projectile the combination of a runway, a detonation-controlling member movable in said runway by rotation of the projectile, and means rendered ineffective by the rotation of the projectile holding said detonation-controlling member against such movement.

In testimony whereof I have hereunto set my hand.

JOHN B. SEMPLE.
